UNITED STATES PATENT OFFICE.

CHARLES J. WANGLER, OF ST. LOUIS, MISSOURI.

ROTARY BEVEL-SHEARS.

SPECIFICATION forming part of Letters Patent No. 686,641, dated November 12, 1901.

Application filed May 8, 1901. Serial No. 59,229. (No model.)

To all whom it may concern:

Be it known that I, CHARLES J. WANGLER, a citizen of the United States of America, and a resident of the city of St. Louis, and State 5 of Missouri, have invented certain new and useful Improvements in Rotary Bevel-Shears, of which the following is a specification.

This invention relates to that class of power-shears for beveling the edges of heavy 10 metal plates in which a pair of power-driven cutter-disks are employed to trim off to a bevel the edges of the boiler-plate, crown-sheets, and the like heavy plate-metal articles.

15 The present improvement has for its object to provide a simple, durable, and efficient construction and arrangement of parts with which the lateral strain upon the carrying-shafts of the cutters is very efficiently avoided and the usual tendency of the same to spring and to break at a point adjacent to the cutters and unduly wear the shaft-bearing is avoided and which in addition affords a convenient and ready means for adjusting 20 the parts to circular work of varying diameters or radii, all as will hereinafter more fully appear and be more particularly pointed out in the claims. I attain the above-mentioned objects by the construction and 25 arrangement of parts illustrated in the accompanying drawings, in which—

Figure 1 is a side view of a rotary bevel-shears with parts in section, illustrating the present improvement; the lower or base portion 30 of the main frame or housing being omitted; Fig. 2, an elevation in the direction indicated by the arrow in Fig. 3 of the shifting mechanism for the adjustable roller by which the work is guided during the cutting or beveling operation. Fig. 3 is a fragmentary horizontal section at line $\alpha\alpha$, Fig. 1.

Similar numerals of reference indicate like parts in the different views.

Referring to the drawings, 1 represents the 35 main supporting-frame or housing of any usual and approved construction, preferably of the hollow-shell form shown, and provided with the usual boxes, pivot-hubs, &c., for the shafts and other mechanisms of the machine.

50 2 is a shaft arranged horizontally in bearings in the main frame and carrying at its forward end the lower cutter-disk, as herein-

after described, and at its rear end provided with a bevel gear-wheel 3 and a large spur gear-wheel 4, connected by a suitable intermediate speed-reducing gear-wheel to a counter-shaft carrying the driving-belt pulley 5 of the machine and the companion idler-pulley 6 thereof.

7 is an obliquely-arranged shaft carrying at 60 its forward end the upper cutter-disk, as hereinafter described, and at its rear end provided with a bevel gear-wheel 8 of the same diameter as the bevel gear-wheel 3 and meshing therewith, so as to receive positive rotation therefrom.

9 is a tubular housing or support for the upper oblique cutter-carrying shaft 7, provided with front and rear bearing-bushings 10 and 11 therefor and pivoted at its rear end 70 in the main frame by means of a transverse pivot-pin 12, so as to be capable of a slight radial adjustment.

13 is a capstan or other like screw having a screw-bearing in the upper and forward end 75 of the main frame, with its lower end adapted to engage against the forward end of the tubular guide housing or support 9 to impart a positive downward adjustment to the same in the operation of adjusting the rotary cutting-disks of the present improvement.

14 is a lever pivoted immediately below the tubular housing or support 9, with its forward arm engaging beneath the forward portion of said support 9, and preferably by 85 means of a friction-roller 15, bearing upon an inclined lug or track 16 on said support, as illustrated in Fig. 1.

17 is a counterpoise-weight carried on the rear and longer arm of the lever 14 and adapted to overbalance the weight or downward tendency of the upper cutter-carrying shaft and its support and impart an upward tendency to the forward end of the cutter-carrying shaft and its tubular bearing-support 95 against the downward tendency of the same by gravity. Such weight is made adjustable by means of a series of serrations 18', formed in the long arm of the lever 14 and adapted to engage in the correspondingly-formed bore 100 of the weight 17, as clearly illustrated in Fig. 1.

The cutter-disks of the present invention will comprise constructions as follows:

18 is the lower cutter-disk, formed with

counterpart chamfered edges 19, so as to be reversible, such chamfered edges having in the present invention a bevel corresponding to a line drawn at right angles to the axis of 5 the upper cutting-disk, as clearly illustrated in Fig. 1. Between the chamfered edges 19 the cutter-disk 18 will have an intermediate flat peripheral portion 20, the point of meeting between which and the beveled surfaces 10 aforesaid will constitute the cutting edge of the cutter-disk, while the flat peripheral portion 20 will constitute a holder or support for the work during the beveling operation.

21 is the upper cutter-disk, having a flat 15 periphery of a length corresponding to the thickness of the disk, so as to render the same capable of reversal to replace an edge already worn by continued cutting. The cutter-disks will be secured in any suitable manner to 20 their respective shafts, preferably by means of nuts 22, screwing upon the reduced screw-threaded forward ends of the carrying-shafts, as illustrated in Figs. 1 and 3.

23 is a work guide or bar provided at its 25 forward guide end with a friction-roller 24 and arranged to slide in a horizontal plane level with the cutting-point of the pair of cutters or shears of the machine and preferably with its longitudinal axis arranged obliquely to the longitudinal axis of the machine.

25 is a stationary guide-frame for the work guide or bar 23, secured to an angle-bracket 26, which is secured in turn to the side of the 30 main frame of the machine.

27 is a pair of counterpart ratchet-sectors secured in separated relation to the bracket 26, the curved surfaces of which are provided with locking ratchet-teeth, as shown.

40 28 is a hand-lever pivoted at one end between the ratchet-sectors 27 by a pivot-bolt 29 and provided at its handle end with a lever-grip 30, having operative link connection 31 with the ratchet-dog 32, pivoted to the lever, 45 and adapted to have operative engagement with the teeth of the ratchet-sectors 27, so as to lock the said lever in any desired position.

33 is a stud or bolt secured in a lateral manner to work-guide 23 and arranged to have 50 movement in the longitudinally-elongated slots 34 in the ratchet-sectors 27 and a corresponding slot in the guide-frame 25. Operative engagement between the operating-lever 28 and the lateral stud or bolt 33 is had 55 by an orifice or slot in said lever, which will be elongated vertically to permit of the vibratory movement of such lever.

I have shown in the drawings the above-described adjusting mechanism as arranged 60 vertically at the side of the machine. It is, however, within the province of the present invention to arrange the same in any other plane that the circumstances or its particular location may suggest.

65 Having thus fully described my said invention, what I claim as new, and desire to secure by Letters Patent, is—

1. In a rotary bevel-shears, of the character herein described; the combination of a pair of cutter-disks arranged obliquely to each other, the lower disk being carried on a horizontal shaft, and the upper, on a shaft oblique thereto; the upper disk having a cylindrical periphery and the lower disk having a cylindrical periphery beveled at its rear edge, the 70 intersection of such beveled edge with cylindrical periphery constituting the cutting edge of said lower disk, while such cylindrical lower disk—with its connecting-shaft and setting—constitutes a support for the material as 75 it is fed to the shears; a supporting-frame, and gearing connections imposing positive movement on both shafts, substantially as set forth.

2. In a rotary bevel-shears, of the character 80 herein described; the combination of a pair of cutter-disks, arranged obliquely to each other; the lower disk being carried on a horizontal shaft, and the upper, on a shaft oblique thereto, the upper disk having a cylindrical periphery, and the lower disk having a cylindrical periphery beveled at its front and rear edges, the intersection of such rear bevel edge with cylindrical periphery constituting the cutting edge of said lower disk while such 90 cylindrical lower disk with its connecting-shaft and setting constitutes a support for the material to be beveled as it is fed to the shears; a supporting-frame, and gearing connections, imposing positive movement on both 95 shafts, substantially as set forth.

3. In a rotary bevel-shears of the character herein described; the combination of a pair of cutter-disk-carrying shafts arranged obliquely to each other, and having gearing connections which afford positive movement to both shafts, on the forward ends of which the cutter-disks are mounted obliquely to each other; the upper disk having a cylindrical periphery and the lower disk having a cylindrical periphery beveled at its rear edge; the 105 intersection of such bevel edge with the cylindrical periphery constituting the cutting edge of said lower disk; and the outer edge of the upper disk constituting the cutting 110 edge thereof; the lower cylindrical disk with its connecting-shaft and setting affording a support for the material as it is fed to the shears; together with a supporting-frame, all 115 substantially as described.

4. In a rotary bevel-shears, the combination 120 of a pair of cutter-disk-carrying shafts, arranged obliquely to each other and having gearing connections which afford positive movement to both shafts, on the forward ends 125 of which the cutter-disks are mounted obliquely to each other, the upper disk having cylindrical periphery, and the lower disk having cylindrical periphery beveled, at its front and rear edges, the intersection of such rear 130 edge with the cylindrical periphery, constituting the cutting edge of said lower disk; and the outer edge of the upper disk constituting the cutter edge thereof; the lower cy-

lindrical disk—with its connecting-shaft and setting—affording a support, for the material as it is fed to the shears; together with a supporting-frame, all substantially as shown and described.

5. In a rotary bevel-shears of the character herein described, the combination of a main frame, a lower cutter-carrying shaft journaled in the main frame, an upper cutter-carrying shaft journaled in tubular housing pivoted at its rear end in the main housing, means for adjusting the forward end of such housing, a lever pivoted in the main frame with its forward end engaging beneath the 10 said housing, and a counterpoise-weight secured to the rear and longer arm of said lever, substantially as herein described.
- 15 6. In a rotary bevel-shears of the character

herein described, the combination of a main frame, a lower cutter-carrying shaft journaled in the main frame, an upper cutter-carrying shaft journaled in tubular housing pivoted at its rear end in the main housing, 20 means for adjusting the forward end of such housing, a lever pivoted in the upper frame 25 with its forward end engaging beneath the said housing by means of a friction-roller and an inclined track, and a counterpoise-weight secured to the rear and longer arm of said lever, substantially as herein described.

Signed at St. Louis, Missouri, this 3d day of May, 1901.

CHARLES J. WANGLER.
